PILE FABRIC WEAVE

Garfield J. Underwood, Amsterdam, N. Y., assignor to Mohawk Carpet Mills, Inc., Amsterdam, N. Y., a corporation of New York

Application February 8, 1932. Serial No. 591,513

2 Claims. (Cl. 139—401)

This invention relates to pile fabrics of the tapestry and Wilton types and is concerned more particularly with a novel pile fabric which is superior to prior fabrics of the same kind in that 5 it has increased thickness and softness in the back, its pile tufts are bound more securely in place, and its general appearance resembles that of fabrics of the more expensive chenille weave. Wilton and tapestry fabrics as now ordinarily 10 woven may be produced with fine clean-cut designs in the face pattern but these fabrics are inferior to those of the chenille variety because the latter, with their characteristic basket weave on the back, have a softer body of greater thickness and a pile surface which is more luxurious 15 and of better appearance. While chenille fabrics are highly satisfactory in the respects mentioned, the use of chenille strips for the pile adds substantially to their cost and limits the 20 kind of designs that can be employed since there is an inherent tendency in such fabrics to irregularity in the pattern, which is likely to be objectionable, particularly in fabrics of the best grade. Also, chenille fabrics as heretofore 25 commonly woven do not have their pile tufts firmly bound in place and the life of such fabrics is liable to be shortened by the pulling out of the tufts.

Attempts have been made in the past to devise 30 methods of weaving fabrics which combine the desirable features of these two types but, so far as I am aware, these efforts have not resulted in success either because the tuft yarns in such fabrics were not bound sufficiently securely so 35 that they would not pull out or else because noticeable marks were visible in the pile surface due to uneven binding of the weft yarns, detracting from its appearance.

The present invention is accordingly directed 40 to the provision of a fabric of novel weave which may have both the fine designs in the face pattern, possible with Wilton and tapestry weaves, and the soft heavy back characteristic of chenille materials, these desirable results being obtained 45 by an improved method of interlacing the binder warps which also insures that the tuft yarns will be firmly bound in place. The new fabric has the basket weave back of chenilles and may be woven with heavy woolen weft, and, because of 50 the manner in which the pile tufts are bound, an excellent and uniform covering of the body of the fabric by the face yarn is obtained and the pile surface is soft and luxuriant.

The new fabric includes stuffer warps, weft 55 shots arranged in upper and lower series lying

respectively above and below the stuffer warps, pile yarns held in place beneath the upper weft shots, and binder warps which bind the weft shots in the fabric. The binder warps are divided into a plurality of sets and these warps 60 are so interlaced in the fabric that each weft shot of the upper series is bound in place by warps of two sets alternating along the shot and with each of the warp threads lying in the interval between a pair of pile tufts. Successive 65 weft shots of the upper series are bound in the same manner but by warp threads of different sets with a result that, in each longitudinal row of intervals between rows of pile tufts, there are warp threads of at least two sets 70 in alternation binding the upper weft shots. The weft shots of the lower series are each bound by warp threads of at least two sets arranged in alternation along the shot but crossing beneath the shot in pairs with the threads 75 of a pair lying in contact and with substantial lengths of the shot unbound between successive pairs. Successive shots of the lower series are bound by warp threads of different sets and the crossings of the pairs of binder warps 80 beneath successive lower shots are in staggered relation. With this construction, each weft shot of the upper series is bound at every point between adjacent pile tufts, while each weft shot of the lower series is bound by pairs of binder 85 warp threads with the pairs spaced apart a distance equal to the width of two or more pile tufts. Also, no weft yarn of the upper series is bound by the same combination of warps employed in binding any weft yarn of the lower 90 series. As each upper weft shot is crossed by a binder warp on each side of each pile tuft, the tufts are bound tightly in place and at the same time the back of the fabric has the customary basket weave of a chenille fabric with 95 the accompanying softness and thickness of the latter. The pile of the new fabric is produced by pile yarns incorporated in the fabric in the customary manner employed in connection with the weaving of tapestry or Wilton fabrics, and the new fabric may, accordingly, have the fine sharp designs characteristic of those materials and not attainable in chenille goods.

For a better understanding of the invention, reference may be had to the accompanying drawing in which:

Fig. 1 is an enlarged sectional view of a fabric of the tapestry type woven in accordance with the principles of the invention, the elements of 100 105 110

the fabric being separated to make clear the method of weaving;

Fig. 2 is a sectional view at right angles to Fig. 1;

5 Fig. 3 is a bottom view of the fabric illustrated in Fig. 1;

Fig. 4 is a view similar to Fig. 3 but illustrating the back of the fabric and showing the elements in their normal relation in the finished 10 product;

Fig. 5 is a view similar to Fig. 1 showing a fabric of the Wilton type; and

Fig. 6 is a sectional view at right angles to Fig. 5.

15 The tapestry fabric woven in accordance with my invention and illustrated in Figs. 1 to 4, inclusive, includes heavy woolen weft yarns 10 lying in upper and lower series respectively above and below stuffer warps 11. In the fabric 20 shown, the stuffers are of four-ply but the number used is not important and any suitable number may be employed. The fabric includes pile tufts 12 which are made by inserting pile yarns in the fabric during the weaving operation, looping these yarns around the weft shot of the upper series, and shearing the yarns at the desired height.

25 The weft yarns are held in place in the fabric by means of binder warps arranged in four 30 series and controlled by separate heddles. The warps of the four series are respectively designated 14, 15, 16, and 17, and the warps of each series cross above alternate weft shots of the upper series and beneath alternate weft shots 35 of the lower series.

40 On reference to Figure 3, it will be seen that the warp 14 passes over the upper weft shot 18, under the lower weft 19 and the upper weft 20, over the lower weft 21 and the upper weft 22, and under the lower weft 23. The warp 45 15 is paired with the warp 14 between the same rows of pile tufts, and passes under the upper weft shot 18 and the lower weft 19, over the upper weft 20 and the lower weft 21, and under the upper weft 22 and the lower weft 23. Of the other pair of warps, the warp 16 passes 50 over the upper weft 18 and the lower weft 19, under the upper weft 20 and the lower weft 21, and over the upper weft 22 and the lower weft 23, and the other warp 17 of this pair passes under the upper weft 18, over the lower weft 19 and the upper weft 20, under the lower weft 21 and the upper weft 22, and over the lower weft 23.

55 With this arrangement, each weft shot of the upper series is bound in the fabric by warp threads of two series, and the warp threads crossing this weft shot lie spaced apart at substantially uniform distances with pile tufts 12 looped around the weft shot between adjacent warp threads. Each pile tuft is thus engaged by a pair of warp threads in contact with its opposite faces and is firmly held in position thereby. Alternate weft shots of the upper series 60 are bound by the same binder warps as, for example, upper weft shot 18 is bound by warps 14 and 16, and upper weft shot 22 is also bound by warp threads 14 and 16. Consecutive weft shots of the upper series are bound by different warp threads, as for example, upper weft shot 20 is bound by warps 15 and 17 and the next upper weft shot 22 by warps 14 and 16. In each case, the warp threads binding at upper weft shot are spaced a substantial distance apart 65 and the distances between the points where the

warp threads cross the upper weft shot are substantially uniform.

70 Alternate weft shots of the lower series are bound by the warp threads of the same two series, for example, the lower weft shot 23 is bound by warp threads 14 and 15. Consecutive weft shots of the lower series are bound by different warp threads, the lower weft shot 21 which lies next to the lower weft shot 23 being bound by warp threads 16 and 17. At the points where the binder warps cross beneath the lower weft shots, the warps lie in pairs, the members of which are substantially in contact, as shown in Fig. 4, and there are thus substantial lengths 75 of lower weft shots exposed between adjacent pairs of binder warps crossing beneath them.

80 A fabric woven in the manner described has the basket type of weave on the back typical of chenille fabrics and its back is thick and soft because of the substantial lengths of weft 85 yarns exposed between adjacent pairs of binder warps. The thickness and softness can be increased to an extent such that the fabric closely resembles Chenille materials in these respects by the use of heavy woolen weft yarns. The 90 fabric, however, is superior to chenille material in that its pile tufts are bound firmly in place and marks on the pile surface are avoided. Also, the pile yarns are introduced into the fabric in accordance with the regular 95 practice employed in weaving tapestry goods and consequently finer and sharper designs in the face pattern may be obtained than is possible in chenille fabrics.

100 The method of weaving described above in connection with the production of tapestry fabrics may also be employed in weaving Wilton goods and a Wilton fabric woven in accordance with the principles of the invention is illustrated in Figs. 5 and 6. This fabric includes weft shots 105 10 in upper and lower series above and below four-ply stuffers and there frames of face yarn 25. It is to be understood that the number of frames of face yarn used may be varied as desired just as the number of stuffers employed 110 will be varied in accordance with the type of fabric to be produced. In the Wilton fabric the face yarns 25 are lifted out of the fabric at the desired places to form loops which produce the pile, these loops being cut, if desired, to form 115 125 pile tufts 26. Each pile yarn in the fabric is bound in place by a plurality of weft shots of the upper series and the portions of those yarns which form tufts are engaged on opposite sides 120 by binder warps so that a good binding action 130 is obtained. The binder warps are interlaced in the fabric in the manner previously described in connection with tapestry weaving and provide the basket weave back typical of chenilles. In 135 both the Wilton and tapestry goods, the improved method of binding the weft shots and the pile yarns in place produces a better and more uniform covering of the body by the face yarn.

140 In weaving the new fabrics, the usual Wilton or tapestry looms may be employed, these looms being provided with four heddles, one for each series of binder warps, and the binder warp beam is wound with a two-play warp with two ends for each split or space in the reed. With 145 this arrangement, and with the heddles manipulated to produce the interlacing described, a perfect bind on each side of the pile tufts is provided together with a double binding for consecutive back wefts with the crossings in staggered relation.

I claim:—

1. A pile fabric which comprises stuffer warps, weft shots in upper and lower series lying, respectively, above and below the stuffer warps, 5 the weft shots in at least said lower series being of heavy wool, pile yarns held beneath weft shots of the upper series and having portions extending above the face of the fabric to produce a pile, and binder warps for binding said 10 weft shots in the fabric, said binder warps individually binding each weft shot of the upper series to the fabric in each interval between adjacent pile tufts and binding each weft shot of the lower series in pairs, the warps of each pair 15 lying substantially in contact and the pairs being spaced along the weft shots a distance of at least the width of two pile tufts.

2. A pile fabric which comprises stuffer warps,
